LOOM SHUTTLE

John J. Kaufmann, Jr., Greenville, S. C., assignor to Steel Heddle Manufacturing Company, Philadelphia, Pa., a corporation of Pennsylvania

Application September 19, 1947, Serial No. 774,901

8 Claims. (Cl. 139—215)

1

This invention relates to shuttles for looms, and it relates more particularly to improved threading means in shuttles of the automatic type.

In the shuttles which are used in modern types of high speed automatic looms, a threading block is usually provided at the rear end of the shuttle. Such threading blocks are made in various shapes and styles and are designed to cause the filling yarn, after an empty bobbin has been displaced and a full one substituted therefor, to be threaded automatically through the threading block and thence through a side delivery eye. The threading action usually starts on the first pick of the shuttle and is completed on the first return pick thereof.

The present invention contemplates the use of a threading block, the main or body portion of which is made of a casting of iron, brass, or other suitable material having novel tensioning means for the filling yarn, novel takeup mechanism therefor, and a novel construction and arrangement of the outlet eye.

The principal object of the present invention is to provide a novel and efficient form of threading block for automatically threading loom shuttles, the main or body portion of which may be made of a casting of iron, brass, or other suitable material, having incorporated therein improved tension devices, improved takeup mechanism and an outlet eye formed directly in the threading block casting.

A further object of the invention is to provide, in a shuttle threading block of the character aforesaid, a novel form of tension pads which will function effectively not only as a first pick tension device, but also for the purpose of maintaining a constant frictional tension on the filling yarn after the shuttle has been completely threaded.

A further object of the invention is to provide, in a shuttle threading block of the character aforesaid, improved means for taking up slack in the filling yarn whenever the same occurs during the operation of the loom, particularly at the times when reversal of movement of the shuttle takes place.

A further object of the invention is to provide, in a shuttle threading block of the character aforesaid, a novel form and arrangement of the side outlet eye, the same being formed directly in the threading block casting.

The nature and characteristic features of the invention will be more readily understood from the following description, taken in connection with the accompanying drawing forming part hereof, of which:

2

Figure 1 is a top or plan view of the threading end portion of a loom shuttle having a threading block provided with means embodying the main features of the present invention;

5 Fig. 2 is a side elevation thereof;

Fig. 3 is a longitudinal central sectional view thereof;

10 Fig. 4 is a transverse section taken approximately on the line 4—4 of Fig. 1;

Fig. 5 is a transverse section taken approximately on the line 5—5 of Fig. 1;

Fig. 6 is a transverse section taken approximately on the line 6—6 of Fig. 1;

15 Fig. 7 is a perspective view, enlarged, illustrating a pair of tension pads of the novel form contemplated by the present invention, the same being shown detached and slightly separated from each other; and

20 Fig. 8 is a perspective view, enlarged, of the takeup device forming part of the present invention, the same being shown removed from the threading block.

It should, of course, be understood that the description and drawing herein are illustrative 25 merely, and that various modifications and changes may be made in the structure disclosed without departing from the spirit of the invention.

Referring to the drawing, in the particular 30 embodiment of the invention therein shown, the shuttle body 10 may be made of wood or other suitable material and has the usual bobbin chamber 11 in which the bobbin 12 is held by the usual means (not shown) whereby it may be readily discharged and a new bobbin substituted as the filling yarn runs out from time to time.

The threading block 13 comprises a casting, 35 preferably made of material such as cast iron, although brass or other material may be used, as desired. Said threading block is mounted in a complementally shaped recess 14 in the rear end of the body portion 10 of the shuttle.

The body portion of the threading block 13 is provided with a longitudinal thread channel 15 through which the filling yarn passes to the side delivery eye 16 during the weaving operation.

40 The threading block 13 is provided at its rear end, on one side, with a rearwardly extending prong 17, having an enlarged head portion 18 and, on the other side, with the usual rearwardly extending horn portion 19 coacting with the head portion 18 of the prong 17, there being a guide slot 20 between the end of the horn 19 and the side surface of the head portion 18 of the prong 17.

45 At the forward end of the threading block 13,

that is, at the end thereof toward the bobbin chamber, there is provided a lug portion 21 overhanging the thread channel and serving to close the same with the exception of the thread entrance slot 22 provided on one side of the lug 21.

The thread entrance channel thus provided at the forward end of the threading block is countersunk as at 23 to facilitate the passage of the thread into the main thread channel 15 as the shuttle travels back and forth across the loom in the weaving operation.

Each of the tension pads 30 contemplated by the present invention is provided with two arms disposed substantially at right angles to each other, the one of said arms 31 being disposed at a slight angle to the horizontal, and the other of said arms 32 being disposed at a slight angle to the vertical. The nearly horizontal arm 31 is also preferably tapered toward the forward end.

Each of the tension pads 30, at the forward end of the horizontal arm 31 is provided with a sidewise extension 33. The sidewise extensions 33 are positioned in suitable apertures 34 in the side walls of the threading block. At the lower end of the nearly vertical portion 32 of each tension pad there is provided an aperture 35 through which a pin 36 extends for the purpose of maintaining the tension pads in their proper locations within channel 15 of the threading block. The ends of the pin 36 are mounted in the side walls of the threading block 13 in the usual manner.

The tension pads are impelled toward each other in the usual manner by means of springs 37, which are adjustably mounted in suitable apertures in the side walls of the threading block 13.

The novel takeup device of the present invention is mounted in the thread channel 15 of the block 13 and is shown in enlarged perspective in Fig. 8 of the drawing. The same comprises a U-shaped member 40 having one arm 41 thereof secured in a cylindrical plug 42 which is pivoted in one of the side wall portions of the body of the threading block 13. The other arm 43 of said member is in the end of a stud shaft 44 which is pivotally mounted in a bushing 45 which in turn is mounted in the other side wall portion of the body of the threading block 13. The stud shaft 44 has an extension provided with a slot in its outer end by means of which one end of an elastic rubber strand 46 is secured. The other end of the rubber strand 46 is secured in a slotted head portion of a screw 47 which is threaded with a tight fit in the body portion of the threading block, the arrangement being such that the tension of the elastic strand 46 on the stud shaft will tend to rotate the same and thereby raise the transverse arm 48 of the U-shaped member of the takeup device to its uppermost position.

One side arm 43 of the U-shaped member of the takeup device is provided with a sidewise extending lug 49 adapted to encounter a portion of the casting of the threading block at the upper limit of its movement.

The other side arm 41 of the U-shaped member 40 also has an offset in which is mounted an upwardly extending pin 50 around which the filling yarn passes on its way to the outlet eye 16 during the operation of the loom.

Heretofore, in the construction of the threading blocks of automatically threading loom shuttles of this general type, it has been customary to provide, on the lower side of the rearwardly extending horn member, an inclined edge which served to guide the filling yarn, on the first re-

turn pick of the shuttle, downwardly into the outlet eye. The outlet eye however was customarily mounted in the wooden body portion of the shuttle at the lower end of the downwardly inclined edge of said horn member, and was usually protected against wear by inserted steel pins or eyelets.

In the device of the present invention, the side delivery eye 16 is provided directly in the lower end of the downwardly extending portion of the horn member, the same comprising an opening 51 having an eyelet 52 made of hard material inserted therein. The eyelet 52 is also open as at 53 on the lower side, being suitably shaped to guide the thread after it has traveled downwardly along the lower inclined edge 54 of the horn portion. After the thread has passed into the eye proper, it will, in the normal run of the shuttle, move outwardly through the eyelet 52 as the shuttle is moved back and forth across the loom during the weaving operations.

The operation of the threading block of the present invention should be readily understood. On the first pick of the shuttle, as the same travels across the loom, the end of the yarn having been previously secured to a fixed part at the side of the loom structure, the same will first be drawn downwardly into the thread channel of the threading block through the slot 22 and will pass under the lug 21.

In its passage the yarn will encounter the forward ends of the nearly horizontal arms of the tension pads, and will pass between the same and at the same time the yarn will pass through the slot 20, between the forward end of the horn member 19 and the coacting portion of the rearwardly extending prong 17 and will, at the same time, depress the rear end of the U-shaped member 40 of the takeup device.

As the shuttle passes across the loom on the first pick the nearly horizontal arms 31 of the tension pads 30 will effectively serve as a first pick tension device.

On the first return pick of the shuttle, after the reversal of its movement takes place, the filling yarn will be caused to pass downwardly under the lower inclined edge 54 of the rearwardly extending horn 19 and guided thereby until the same passes into the slot 53 of the eyelet 52 which constitutes the delivery eye of the shuttle.

After the yarn has been fully threaded in the shuttle, as aforesaid, upon the subsequent movements of the shuttle, as the same passes back and forth across the loom, the yarn will pass outwardly through the delivery eye, and as the reversal of movement takes place, the takeup device will serve to take up any slack which may occur in the filling yarn.

I claim:

- An automatically threading loom shuttle having a threading block the main or body portion of which comprises a casting provided with a thread channel extending longitudinally therethrough, said threading block having a side outlet eye for the passage of the filling yarn, the rear end portion of said threading block being provided with coacting lug and horn portions for guiding the yarn downwardly in its passage through the threading block, the underside of the horn portion having an inclined edge for guiding the yarn into the side outlet eye, a takeup device mounted in the thread channel comprising a U-shaped member having a transverse bar extending across the thread channel and side

arms the ends of which are pivotally mounted in the side walls of the casting, elastic tension means for raising the transverse bar of said takeup device, and a pin mounted on one of the side arms of the takeup device and around which the yarn passes to the side outlet eye.

2. An automatically threading loom shuttle having a threading block the main or body portion of which comprises a casting provided with a thread channel extending longitudinally therethrough, said threading block having a side outlet eye for the passage of the filling yarn, means for guiding the thread into the side outlet eye, a takeup device mounted in the thread channel comprising a U-shaped member having a transverse bar extending across the thread channel and side arms the ends of which are pivotally mounted in the side walls of the casting, elastic tension means for raising the transverse bar of said takeup device, and a projecting member mounted on one side of the takeup device and around which the yarn passes to the side outlet eye.

3. An automatically threading loom shuttle having a threading block the main or body portion of which comprises a casting provided with a thread channel extending longitudinally therethrough, said threading block having a side delivery eye for the passage of the filling yarn, a takeup device mounted in the thread channel comprising a U-shaped member having a transverse bar extending across the rear end of the thread channel, and side arms having pivot members at their forward ends said pivot members being pivotally mounted in the side walls of the casting, and elastic tension means for raising the transverse bar of said takeup device.

4. An automatically threading loom shuttle having a threading block the main or body portion of which comprises a casting provided with a thread channel extending longitudinally therethrough, a takeup device mounted in the thread channel comprising a U-shaped member having a transverse bar extending across the thread channel, and side arms the ends of which are pivotally mounted in the side walls of the casting, elastic tension means for raising the transverse bar of said takeup device, and a projecting member mounted on one side of the takeup device and around which the yarn passes.

5. An automatically threading loom shuttle having a threading block the main or body portion of which comprises a casting provided with a thread channel extending longitudinally therethrough, a takeup device mounted in the thread channel comprising a U-shaped member having a transverse bar extending across the thread channel, and side arms the ends of which are pivotally mounted in the side walls of the casting, elastic tension means for raising the transverse bar of said takeup device, and a projecting member on one side of the takeup device and around which the yarn passes to the delivery eye of the shuttle.
